United States Patent Office.

PETER McCOLLUM, OF FAYETTE, MISSOURI.

Letters Patent No. 91,651, dated June 22, 1869.

IMPROVEMENT IN PORTABLE FENCE.

The Schedule referred to in these Letters Patent and making part of the same.

To all whom it may concern:

Be it known that I, PETER McCOLLUM, of Fayette, in the county of Howard, and State of Missouri, have made certain new and useful Improvements in Portable Fence; and I do hereby declare that the following is a full and correct description thereof, reference being had to the accompanying drawings, and to the letters of reference marked thereon.

The object of this invention is to form a fence, the parts whereof are independent panels, which may readily be connected or disconnected, and which may therefore be readily adjusted in any required form or position, and, after use, may easily be removed and transported to a place of storage, or to a second place of adjustment and use.

The nature of this invention is in the manner of joining and locking the independent panels to each other by locking-hooks and a sliding-key, and in the arrangement of battens, against which the pressure of said locking-devices may be exerted when there is an effort to disconnect the parts by lateral pressure.

To enable those herein skilled to make and use my said invention, I will now fully describe the same, referring herein to the accompanying—

Figures 1 and 2, as elevations of consecutive independent panels, and to

Figures 3 and 4, as elevation and plan respectively, showing the panels locked together.

In all said figures the manner of locking, and the construction of parts therefor, is shown in full only on the adjoining ends of the consecutive panels.

I form the one panel A of a series of horizontal bars, *a*, attached in the ordinary manner to the vertical ribs or battens *b*.

In this panel I use a batten, *b'*, on the reverse side of the bars *a*, thus gaining, by the contiguous batten *b* and *b'*, double points of attachment and support for the locking-hooks or brackets B, the connection of said brackets to the battens *b* and *b'* being made between the slats *a*, and by screws, nails, or otherwise.

The brackets B are arranged with raised ends or projections *b''*.

The other panel C is formed of horizontal bars *c* and vertical ribs *d*, generally in a manner similar to the panel A, but the contiguous ribs *d* *d'* are here placed on one and the same side of the bars *c*.

In connecting the said panels, the panel C will be

lifted up so that the hooks B of the panel A may pass between the bars *c*; the panel being then dropped to *a*, rest on the ground, the projecting ends *b* of the said hooks will prevent the withdrawal.

In order, however, to prevent disengagement of said panels more effectually, I arrange the sliding key-piece D, having a slot, *d'*, and held by a pin, *d''*, to the end-rib *b* of the first panel.

This key fits, in width, neatly between the corresponding bars *c* of the second panel, so that when the same is moved forward into its position of proper engagement, indicated in fig. 3, the panel C cannot be lifted up or lowered without carrying with it the panel A also. Then, as the brackets B prevent the panels from being drawn apart in a horizontal movement, the lock will be seen to be complete.

In the position thus achieved, it will be seen that the end rib *d* of the panel C rests and presses upon the bars *a* of the panel A, and the brackets B rest and press upon the rib *d'* of the panel C, and, as said brackets are doubly secured by attachments at the ribs *b* and *b'*, it is plain that the parts are firmly braced against each other, and interlinked, to afford great security against side-pressures, as heretofore stated to be in the nature of this invention.

By withdrawing the key D, the panel C may then be raised and disengaged from the brackets B, and thus a separation of the fence into its independent panels is readily achieved.

The connecting panels will usually form a very obtuse angle with each other, thus forming a zigzag line, but said panels may be placed at any required angle, and thus enclose spaces of any required outline.

Having thus fully described my invention,

What I claim, is—

1. The panels A C, joined by brackets B and the sliding-key D, substantially as set forth.
2. The bars *a*, battens *b* and *b'*, when combined with the bars *c*, and battens *d* and *d'*, and the brackets B, substantially as set forth.

In witness of said invention, I have hereunto set my hand, in the presence of—

PETER McCOLLUM.
